(57) **CLAIM**

The ornamental design for a glass door for clothes drying machine, as shown and described.

DESCRIPTION

FIG. 1 is a perspective view of a glass door for clothes drying machine showing a first embodiment of my new design;

FIG. 2 is a front elevation view thereof;

FIG. 3 is a side elevation view, the opposite side being a mirror image thereof;

FIG. 4 is a perspective view of a second embodiment thereof;

FIG. 5 is a front elevation view thereof; and,

FIG. 6 is a side elevation view, the opposite side being a mirror image thereof.

The broken line showing of the rear portions of a clothes drying machine is for illustrative purposes only and forms no part of the claimed design.
